UNITED STATES PATENT OFFICE.

NAPOLEON DU BRUL, OF CINCINNATI, OHIO, ASSIGNOR TO THE MILLER DU BRUL & PETERS MANUFACTURING CO., OF CINCINNATI, OHIO, A CORPORATION OF OHIO.

CIGAR-MOLD.

1,118,747.

Specification of Letters Patent. Patented Nov. 24, 1914.

Application filed April 9, 1914. Serial No. 830,694.

To all whom it may concern:

Be it known that I, NAPOLEON DU BRUL, a citizen of the United States of America, residing at Cincinnati, in the county of 5 Hamilton, State of Ohio, have invented certain new and useful Improvements in Cigar-Molds, of which the following is a specification.

The object of my invention is to enable the 10 user of cigar molds to avoid applying the lid of the mold in reversed position and thereby bringing the point ends of the cups over the tuck ends of the cavities with resultant damage to both the mold and its contents.

15 In the manufacture of cigars by hand, the cigar bunches are placed in the molds and the lid is placed on the bottom of the mold, after which the mold is subjected to pressure in a suitable press provided for 20 the purpose—in some factories a hand press and in others a hydraulic or powerful screw press operated by power and in which many molds may be introduced for pressing at one time. The molds are carried to the press 25 by the pressmen, who generally do not examine the molds to ascertain whether or not the lids are on right before the pressing is done. Hence, if the lid has been incorrectly placed, that is to say if it has been 30 applied with the point ends of the cups over the tuck ends of the cavities, the sharp edges of the cups not only become damaged themselves, but cut into and ruin both the 35 walls of the cavities and the cigar bunches contained therein, thus causing a double loss.

Many expedients have been resorted to, to prevent the reversal of the lid, such for instance as placing two guiding dowel pins 40 on the under side and at one end of the lid, and one dowel pin on the under side and at the other end of the lid. Again manufacturers have placed a single dowel pin at each end of the lid on the under side, out of 45 alinement with each other and of different diameters. Again they have used pins at one end and a block at the other, and various other devices for the same purpose, but each expedient has been found to be 50 objectionable or has failed to overcome the difficulty.

All guiding devices of this character, so far as I am aware, have been placed on the under side of the lid and are, therefore, concealed from the operator whenever the lid

is right side up, and particularly when he is placing the lid on the mold. Hence there is no visible means of either insuring proper assembly or determining whether or not the lid is in proper relation to the bottom member, after the members are assembled, and the cigar manufacturer is apprised of the improper assembly of the mold only after it has been removed from the press and opened to disclose destruction to both the 65 mold and its contents.

My invention consists in providing a cigar mold with a guide for the assembly of its two members upon which the cups and cavities are mounted, which guide shall so enter 70 into the structure of the mold and lend such distinguishing character to the form of both members of the mold, that the guide shall be appreciable on either member through both the senses of sight and touch, whether the 75 member be inverted or not, and whether the members shall be assembled or separated, and such guide shall, by the relation of its parts on the respective mold members, immediately indicate how the members are to 80 be assembled and after assembling stand as a continuing indicator as to whether they are properly assembled, so that not only may the bunch maker properly apply the lid without delay incident to turning and examining the lid, but the pressmen may detect at a glance any carelessness on the part 85 of the bunch maker in placing the lid.

In the drawings:—Figure 1 is a detail perspective view of the bottom of the mold 90 showing the damage to the cups due to a reversal of the lid; Fig. 2 is a similar view of the top of the mold; Figs. 3 and 4 are views showing the preferred embodiment of the new corner construction, Fig. 3 being a 95 perspective view showing the mold with the parts about to be assembled; and Fig. 4 being a detail perspective view showing the top member of the mold in inverted position which it usually assumes to protect 100 its cup from injury when separated from the bottom member.

Figs. 1 and 2 are accurate drawings, respectively, of the bottom and top members of a cigar mold damaged by the reversal of 105 the lid. The showing in these figures is a correct illustration of the average mold and not of an isolated case. In Fig. 1 it will be seen that the side walls of the cigar bunch cavities are split and slivered at a by the 110

sharp edges of the cups on the lid, while the edges of the cups on the lid are notched at *b*, when the mold is pressed in the press.

The reference numeral 1 designates the 5 bottom of the mold, 2 the cavities formed therein adapted to receive the cigar bunches. The top 3 of the mold is provided with cups 4, the walls of which are very thin. The mold members are held, when assembled, 10 against relative movement by means of the dowel pins 5.

The structure thus far described is old and well known in the art.

In order to eliminate the liability of incorrectly assembling the mold parts, I cut 15 adjacent corners of the bottom and lid preferably as shown at α^1 , α^2 , in Figs. 3 and 4, on an obtuse angle or give them some equivalent corner-configuration extending 20 through both members contrasting with that of the remaining corners which serves of the remaining corners which serves as a guide, which is always in sight on either member and which will, therefore, insure correct assembling of the parts. I 25 find, from experience, that the workman becomes so accustomed to the cut off corner guide, that it prevents him from reversing the lid on the bottom of the mold, and thereby eliminates breakage and ruin of the mold 30 and cigar bunch. This guide not only has an effect upon the eye of the workman but it is recognized through the sense of touch by the workman when he lifts the mold as it is the custom to grasp the mold at the 35 ends, and if the lid is reversed, the ends will not match and this fact will be communicated to the workman as soon as his hand closes over the end of the mold, and even should the error be not recognized at the 40 time of placing the lid, the protruding portion of one mold member associated with the cut-away portion of the other, would promptly attract attention. In this way the error will be detected before the mold is 45 placed in the press.

By constructing a cigar mold with a structural guide extending over adjacent external portions of the two mold members and, therefore, embodying registering guide 50 sections carried by the respective mold members, and by having this guide of such nature that its two parts can be observed when the top is off and to one side, or when the top is being put in position and also 55 when wholly assembled with the bottom, the workman may readily apply the top in correct position when closing the mold, or detect carelessness after it has been improperly closed, and thus avoid the destruction and 60 waste so commonly experienced with molds as heretofore constructed. By making the

guide of two additional faces located on adjacent and corresponding parts of the respective mold members, and contrasting with other similar parts of the mold, the 65 correct manipulation of the top or lid may be determined by the sense of touch and the eyes of the workman are thus left free for observing other features of the work so that the proceeding is correspondingly facilitated.

In using the old styles of mold with an interior guide it becomes necessary for the workman to turn the lid over and look at the shape of the cup to determine which way 75 the cover must be put on to properly register with the cigar bunch cup on the lower member.

My invention provides a very cheap, simple and effective means to avoid losses 80 incident to the damage to the molds and cigar bunches caused by the reversing of the lid of the mold.

I claim:—

1. As a new article of manufacture, a 85 two-part cigar mold comprising top and bottom members carrying the shaped molding cups and cavities; said mold-members having adjacent corners cut-away to give them configurations which conform with 90 each other but contrast with the other corners of the mold, and thereby provide an external structural assembling guide embodying registering guide sections that are adjacent when the mold-members are cor- 95 rectly assembled, and presented in position to signify the relative positions of the mold members when separated as well as when assembled.

2. As a new article of manufacture, a 100 plinth-like cigar mold, comprising top and bottom members carrying the cups and cavities for shaping cigar bunches; said mold being provided with an external structural 105 assembling guide; said guide comprising faces formed in a diagonal plane intersecting both mold-members at one corner of the mold, and thereby forming indexes that conform with each other and contrast with the remaining corners of the mold members 110 and are appreciable through both vision and touch and in positions that bring them into registry when the members are assembled, and that signify the relative positions of the members when separated as well as as- 115 sembled.

The foregoing specification signed at Cincinnati, Ohio, this 30th day of March, 1914.

NAPOLEON DU BRUL.

In presence of—

H. WHYRICH,

F. CHUDOBA.
